UNITED STATES PATENT OFFICE.

SIMEON TRENNER, OF CHICAGO, ILLINOIS.

PROPHYLACTIC AND HYGIENIC ART.

1,208,701.

Specification of Letters Patent. Patented Dec. 12, 1916.

Application filed August 16, 1915. Serial No. 45,773.

To all whom it may concern:

Be it known that I, SIMEON TRENNER, a citizen of Great Britain, and a resident of Chicago, county of Cook, and State of Illinois, United States of America, have invented certain new and useful Improvements in the Prophylactic and Hygienic Arts, of which the following is a specification.

My invention relates to improvements in containers and dispensers for, and in methods of, packing, distributing, storing and dispensing materials in aseptic and hygienic condition for use in medical, surgical, and other treatments by physicians, surgeons, dentists, or others and in some instances for use as confections, food, etc.

The object of my invention is to provide a system of packing cotton or other materials including applicators in an aseptic or hygienic condition and preserving and dispensing same in such condition. The system provides for sterilization, storage, transportation, dispensing and use whereby the materials when withdrawn from the containing case may be safely used. In other words, it is my object to provide a practical system of packing, sterilizing, protecting and dispensing such materials, which shall eliminate in so far as possible the danger of contamination or deterioration by pathogenic or putrefactive organisms, dust, moisture or other means, particularly under circumstances when it is necessary that the materials be handled and used by those not versed in or negligent of the dangers of contamination incident to such use and without the knowledge and skill necessary to protect against infection.

A further object of my invention is to provide an improved carton or box adapted to contain aseptic or hygienic material and so constructed and arranged that the possibility of the contamination of the contained materials is reduced to a minimum and in which the materials are so packed and arranged that they may be withdrawn from the carton as needed without contamination or deterioration of the part withdrawn or of the remaining materials.

50 A further object of my invention is to provide a plurality of pledges carried on suitable applicators or handles and so arranged or packed within a carton or container and preserved in aseptic condition that they may be withdrawn from the container one at a time without any danger of

contaminating either the plegget which is to be used or the pledges which remain in the container.

My invention resides in a system of packing, sterilizing, protecting and dispensing materials in aseptic and hygienic condition for use in medical, surgical and biologic treatments and operations and in some instances for use as food or medicine, whereby 60 the materials may be readily removed from the container as required for use, and whereby the material which remains in the container as well as that withdrawn is protected against contamination from organisms in the air and by direct or indirect contact with infected surfaces or bodies and by moisture in the air.

Further, my invention consists in a box, carton or container adapted to hold a plurality of aseptic devices or masses connected in a series and so packed or arranged in the carton that the withdrawal of one device from the carton places the next succeeding device of the series in a position to be withdrawn and wherein the container is so constructed and arranged that it has a downwardly extending passage through which the devices are withdrawn.

My invention also consists in a box or carton provided with a main chamber adapted to contain a plurality of aseptic or other devices connected together in a series and provided with a narrow or thin passage through which the series of devices are 80 adapted to be drawn when being removed from the carton, there being an opening connecting the passage with the interior of the carton, and the exit of said passage being arranged at a lower point than that at 85 which the communicating opening is arranged whereby the aseptic devices will travel in a downwardly direction through said passage as they are withdrawn from the carton.

100 My invention also consists in a box, carton or container of the kind and for the purpose above mentioned, the passage through which said devices are drawn being adapted to automatically close upon the 105 devices and the connecting material or strip with a yielding pressure and thus prevent pathogenic germs entering into the carton through said passage.

110 My invention also consists in a method of mounting pledges or other devices for packing within the container, which consists in

arranging the articles in serial connected form and packing them in such a manner that they can be removed from the container with no danger of contaminating them.

5 My invention also consists in a method of packing pledges to prepare them for placement within a suitable carton and which consists in placing the pledges in serial order upon a long strip of paper, the strip 10 being wide enough to fold over the pledges and thus cover them, and the pledges being so held that they may be removed from the strip of paper without necessity of touching any part thereof except the handle.

15 My invention also consists in a plurality of pledges each thereof mounted or secured upon a suitable handle or applicator and arranged in series upon a strip of paper, being arranged parallel with each other and 20 the handles being threaded through suitable openings in the paper whereby the pledges are maintained in their relative positions, the strip of paper being wide enough to be folded over the pledges and their handles 25 to protect them from contamination.

My invention also consists in a system of preparing and packing a series of pledges or other articles, such as strips of cotton, or gauze, cotton rolls, packets of surgical 30 catgut, gauze swabs, compresses, packets of aseptic and antiseptic powders or materials, soap powders, biologic preparations, and emollient materials, chemicals, drugs, gum, candies, or other confections or articles of 35 food and X-ray films or other materials, etc., the articles or packages being connected together by suitable means and adapted to be easily and readily withdrawn from the carton or container, either serially or one at a 40 time, without opening the carton more than sufficient to permit the egress of the articles as they are removed.

45 My invention also consists in the means for and methods of packing, storing and dispensing articles, hereinafter more fully described, and by means of which I am enabled to attain the above mentioned and other objects, and all as more particularly set forth in the appended claims.

50 My invention will be more readily understood by reference to the accompanying drawings, forming part of this specification, and in which:

Figure 1 is a vertical sectional perspective 55 view of a container loaded with sterile or hygienic material, the whole illustrating a typical embodiment of my invention; Fig. 2 is a sectional perspective view similar to Fig. 1 showing the cover removed sufficiently to 60 permit the withdrawal of the sterile material from the container; Fig. 3 is a horizontal sectional view of the container on the line 3—3 of Fig. 2; Fig. 4 is a similar horizontal section on the line 4—4 of Fig. 5; Fig. 65 5 is a vertical perspective section, similar

to Fig. 2, and showing a modified form of container; Fig. 6 is a vertical section of a container illustrating a different form of strip of sterile material; Fig. 7 is a vertical sectional view similar to Fig. 6 and illustrating a modified form of container; Fig. 8 illustrates the manner of packing a plurality of sterile swabs, and shows a plan view of a strip of paper carrying the swabs in separated relation and secured to the paper; Fig. 9 is a plan view of a strip of paper showing a series of swabs secured thereto, the paper being wide enough to fold over the swabs and protect them; Fig. 10 is a transverse sectional view on the line 10—10 of Fig. 8, showing one manner of mounting and protecting the swabs; Fig. 11 is a view similar to Fig. 10, illustrating the manner of mounting and protecting the swabs shown in Fig. 9; and Fig. 12 is a cross-sectional view similar to Figs. 10 and 11 taken on the line 12—12 of Fig. 2, and showing the manner of packing a strip of sterile material, such as cotton or gauze.

It is well known by those versed in the medical and surgical art that pathogenic organisms do not travel through air by their own motion, but are carried with moving air or are caused to fall by gravity, consequently they cannot enter through an air passage in which the air is not moving or upon the enclosing surfaces of the passage enter into a closed container. I have made use of this fact in producing my system of packing, storing, and dispensing materials, articles, or devices in aseptic condition whereby I am enabled to dispense articles for use in medical, surgical and other similar treatments in aseptic condition. I arrange the materials within a closed container either sterilized (or put in aseptic condition) before placement therein or sterilized after being placed therein, and I arrange the container so that there can be no rush or strong current of air into the container at any time and from which the materials, articles or devices can be withdrawn one at a time or in serial order without possibility of contaminating the remaining materials or articles.

Cotton or similar materials, as ordinarily packed and prepared for use in the treatment of wounds, is held within a box or other receptacle whose top can be opened and from which a quantity of the cotton can be withdrawn. Usually the top remains more or less open and the box is in condition to permit the direct entrance by gravity from the air above the box of pathogenic organisms. The cotton has doubtlessly been previously sterilized and before the box has been opened in all probability the cotton is in aseptic condition, but immediately the box has been opened there is present the possibility of contamination.

The usual or common method of producing a pledget for use is to take a sterilized applicator, push it into a mass of cotton and by twisting the applicator secure a small roll of the cotton fiber to the end of the applicator and by the withdrawal of the applicator separating this small roll from the mass, but the mass of cotton from which the small mass is removed is not necessarily 5 in sterile condition for, as before stated, through the repeated opening of the box or container within which the sterile cotton has been stored the contained material is probably in contaminated condition instead of in 10 sterile condition.

It is a quite usual practice to wind the small mass of cotton upon the applicator by means of the fingers of the operator, thus directly contaminating the mass of cotton 15 or pledget from the fingers and unless the fingers which are thus used have been sterilized immediately before, the possibility of contamination is present. The reasoning applies to all articles, devices, or materials 20 which it is desired to use in sterile or hygienic condition and which may be packed in bulk within a container for distribution and use. These materials may very readily include applicators for the making and using 25 of pledges, soap powders and other materials for medical or surgical uses, surgical catgut and other similar materials, cotton or other similar swabs, rolls, compresses or small masses, tooth picks and similar articles, 30 gum, candies or other articles for food, and any other material, article or device for application to or upon the living body. For as is well known, these pathogenic organisms may be easily transplanted 35 from an infected or septic article or material to an open wound, abrasion, cut or sore, being transferred or transplanted from one patient to another and often producing in the transplanted position, results or conditions 40 far worse than that shown or recognized in the patient from whom they were derived.

It is well known that in modern practice a careful practitioner uses all possible means to prevent these pathogenic organisms from 45 being transplanted to a place where they will be likely to multiply to the detriment of the patient and it is of course modern practice to use all due care in applying bandages, gauzes, or other materials, that 50 they shall be in aseptic condition, and various means for this purpose have been devised and are in use at the present time in the best hospitals. My invention, therefore, 55 in so far as it is concerned with medical and surgical materials, relates more particularly to the use, by those not highly versed in the medical and surgical art, and in the knowledge of pathogenic organisms, of articles, devices, and materials in the treatment of 60 wounds, sores, cuts, etc., especially in the 65

home and the workshop and on the battlefield, where it is frequently necessary that first aid shall be given by those not learned in the healing and curative art or to systematize technic and prevent negligence when on occasion the dressing materials are used 70 in rapid succession or in emergencies which may possibly preclude the exercise of the great care ordinarily practised.

Broadly considered, the material or strip 75 A, which is shown in Figs. 1 and 2 is merely illustrative of the materials which may be packed in and be dispensed from my containers. In these two figures I have illustrated them as a continuous strip of material 80 which, as will be made clear herein, may take many forms, and may consist of a continuous strip of cotton or gauze protected by paper or other material or it may consist of a continuous strip of material 85 upon which are secured separated articles which it is desired to dispense in sterile condition. It may consist of a series of separated articles joined by or mounted upon a continuous connector by means of 90 which the articles can be withdrawn from the container one at a time and in serial order. However, my invention is not limited to the necessity of having the sterile articles or material dispensed in a continuous 95 manner or order for my invention, as has been explained, relates to a container from which sterile material is dispensed through a passage which prevents the entrance into the container of pathogenic organisms, and 100 deleterious or infectious insects or dust. Whatever form my container takes for the several uses to which it is adapted, it consists of what may be termed a closed casing within which the sterile articles are held, 105 this casing being provided with an exit passage which, broadly speaking, prevents the entrance into the container of pathogenic organisms, dust-laden air, etc. This passage may take the form of a relatively long, 110 narrow or thin duct either between walls which are relatively rigid, though yielding, or between walls which are quite yielding. In the first form the passage is arranged so that the material in being taken there-through moves in a downwardly direction for the purpose of better preventing the entrance into the container of pathogenic organisms, etc. In the second form, that is, 115 where the passage is made up of walls which are not rigid, it is not so necessary that it be arranged to discharge the material in a downwardly direction, for the walls in this case are adapted to close upon each other and thus prevent any conveyance of pathogenic organisms, etc., into the container, 120 and it should be understood that even discharge passages, as described, are not absolutely necessary provided the passage is 125 so made that it is practically impossible for 130

the pathogenic organisms, etc., to enter the container therethrough.

The drawings illustrate a number of different forms of containers and a number of different forms of contained material, but, as will be clearly shown, they all relate to containers and contained material which fall within the scope of my invention.

It is my object to not only pack, preserve and dispense sterile material and articles without danger of contamination, but also to protect the container itself, particularly during intervals after it has been opened and before the material has been all removed and while it is awaiting further use; consequently my containers are usually provided with an outer removable casing or cover, which protects the projecting end or ends of the contained material during storage periods; but even this outer casing is not necessary in all forms of my container, as will be shown hereinafter.

It is further my object to dispense articles in hygienic condition, as well as in sterile condition, for it will be understood that my container can be so arranged that it will protect its contents against contamination other than that which would result from the presence of pathogenic or putrefactive germs, and it is further my object to protect the contained material in some instances from the effect of moisture, light, dust, etc., so that certain materials may be dispensed in commonly termed "fresh condition." The latter would apply particularly to the dispensing of candies, gum, and such like articles, and to the dispensing of drugs, chemicals, and X-ray films and other articles deterioriously affected by light or moisture. It is further my object to provide a means of dispensing articles in such a manner as to assure their cleanliness and freshness, and that they have not been substituted, handled, tried, tested or worn, by salespeople or customers. In other words, to insure the fact that the articles dispensed thus one at a time have not had contact with any one's hands or person since they were packed ready for shipment.

In the form of my container illustrated in Figs. 1 to 4, the container proper B is a closed rectangular (preferably paste board) box which is provided at one side with a downwardly leading exit or discharge passage b^1 . This passage is formed between the inner wall b^2 and the outer wall b^7 . The wall b^2 extends upwardly from the bottom b^3 of the box and ends near the top wall b^4 , leaving a transverse slot or opening b^5 between its upper end and the upper end of the box, through which the contained material can enter the passage b^1 . The upper edge of this wall is provided with a smooth, round edge or corner b^6 over which the strip of material can be freely drawn. The outer

wall of the exit passage b^1 is formed by a wall b^7 which depends from the top b^4 of the box and extends downwardly terminating at b^8 some distance above the bottom of the box. These two walls, b^2 and b^7 , are yielding to some extent to permit the strip A to be drawn therethrough and are adapted to press upon the strip with a yielding pressure, so that the strip is held against other than intentional movement in the passage and the movement of air into and out of the container is minimized. Furthermore, the strip A is held in the exit passage with sufficient friction to prevent it being forced back into the container as the casing C is withdrawn from the container proper. The strip A normally extends through the passage and its outer end a^1 extends below the lower edge b^8 so that when it is desired to withdraw the strip from the container the extending end a^1 may be grasped for this purpose.

In order to protect the extending end a^1 of the strip A, and to further protect the passage b^8 against the entrance of dust, germ or moisture-laden air into the container, I provide a telescoping casing C which is adapted to fit closely upon the casing B, and is long enough to reach nearly to the bottom of the casing B when placed thereon from the upper end, as clearly shown in Fig. 1. One reason for making the exit passage fairly long is to prevent flies from crawling into the container for it is well known that flies will not go through such a passage, particularly when the passage is dark as in this case. In order to further protect the extending end a^1 of the strip, I form the lower end of the wall b^2 outwardly inclined, as shown at b^9 , so that it will contact tightly with the lower end of the casing C when the latter is in position, thus in a sense sealing the space in which the extending end of the strip A is contained when the casing C is in position upon the container B. As a further precaution against contamination, I preferably provide the bottom b^3 of the container with supporting projections b^{10} , so that when the container is standing upon a support its bottom does not contact with the support except through the projections or feet b^{10} .

In order to protect the contents of the container against moisture, or other means of deterioration, I provide in the upper part of the container, a means of absorbing moisture or a means counteracting other deteriorating agencies, in the form of a suitable absorbing or disinfecting chemical protected by a suitable covering. In Figs. 1 and 2 I have shown the protector D as being a suitable powder d^1 , protected by being contained within an envelop of cotton or other suitable fabric material d^2 , and I have shown this protector as arranged in the space be-

tween the top of the container proper and the casing C; but, as illustrated in Fig. 5, this protector may be advantageously arranged within the upper part of the container proper B itself. In whichever position the protector D is arranged it serves its function of absorbing moisture or protecting the contents against contamination.

As shown in Fig. 1, I preferably seal the outer casing or cover C in position upon the container proper B by means of a glued strip A', which I secure to the lower part of the box and the lower part of the cover, and thus effectually secure and seal the cover in position. And in order that this strip may be moisture-proof, I treat the container after the strip has been placed thereon by formaldehyde or some similar leatherizing chemical and thus make the glue insoluble. I sometimes also paint or cover the whole exterior of the container with glue or some substance and subject it to the action of formaldehyde, cromic acid, alum, or some other water-proofing process, and thus make the container as a whole impervious to moisture. This water-proofing of the container is of importance, both as to protecting the contents against dampness from the outside and, in some instances, to preserve the contents against drying out, for the water-proofing of the container effectually prevents the passage of moisture either into or out of the container.

As shown clearly in Figs. 3 and 4, I usually make the strip A somewhat narrower than the box, so that the walls which form the exit passage may yield sufficiently to permit the withdrawal from the container of the strip of material even when the strip consists of a strip of paper carrying masses or rolls of cotton, or other articles which form lumps thereon which might be difficult to draw through a passage whose walls were rigid.

Fig. 2 shows the casing C lifted up a sufficient distance to permit the ready grasping of the outer end a^1 of the strip A, and it is my custom when using this form to withdraw a sufficient length of the strip, particularly if it consists of a strip of cotton or gauze, and then sever the strip with a pair of shears which have been sterilized, thus preserving the strip of material against contamination. I am careful to sever the strip at such a point that the projecting end a^1 is sufficiently long to permit the grasping thereof when it is desired to remove a further section or part of the strip A. This is clearly shown in Fig. 2.

As indicated hereinbefore, the contained strip may comprise a strip of paper carrying separated articles, and I have illustrated this strip A in Fig. 5 as comprising a strip of paper a^2 carrying at intervals thereon masses of cotton or other articles a^3 . When

I make use of a strip of this character I can readily sever the strip between the articles a^3 by means of a knife c^1 carried upon the lower edge of the casing C. In this instance the casing C is withdrawn sufficiently to permit the grasping of the extending end of the strip and the strip is then withdrawn to remove from the container a sufficient number of the articles a^3 . This having been done the cover C is depressed to the position illustrated in Fig. 5 and the paper carrier is severed by means of the knife c^1 . The cover C is then depressed to its lower position to protect the container until it is desired to again remove some of the contained material. I preferably make the casing C to fit the container proper B tightly enough so that the frictional contact between the two will prevent the casing C from changing its relative position during the cutting operation. As shown in Fig. 5, I sometimes substitute an antifriction roller b^{18} for the rounded edge b^6 over which the strip A is drawn. It will be understood that the strip shown in Fig. 5 may generally illustrate a strip carrying any article in separated relation thereon which it is desired to dispense from the container. For instance, this strip may carry swabs, F, as shown in Figs. 8 to 11, inclusive, these swabs comprising handles f^1 having upon one end thereof a swab or pledget of cotton f^2 and these swabs being mounted in spaced relation upon a strip of paper f^3 and secured thereto by any suitable means, such as a thread f^4 , or by means of pairs of slits f^5 formed in the strip of paper and through which the handles f^1 can be threaded, as shown in Fig. 9. Preferably the paper strip is wide enough to be folded over the swabs, as clearly shown in Figs. 10 and 11, to protect the swabs against any accidental contamination.

It will be readily understood that the paper strip could carry articles other than the swabs, F, such as small containers or envelopes G (Fig. 19) which may contain soap powders, medicinal powders, candy, gum, or any other articles which it is desired to dispense from the container. In fact, these small containers may contain coils or tubes of surgical catgut, shown in Fig. 20, or I may mount the tubes directly upon a dispensing strip. The strip shown in Fig. 2 is shown in a large cross section in Fig. 12. This strip comprises a continuous strip of aseptic cotton or gauze a^4 protected by a paper covering in the form of an elongated strip a^5 which is wide enough to fold over and thus form a continuous tube. I preferably strengthen the tube by means of a glued strip of paper a^6 which continues throughout the whole length of the tube, and is preferably arranged on its underside so that it strengthens the paper tube containing the cotton and provides a tough surface or wall

to contact with the upper edge of the wall b^2 over which the strip is drawn as it is removed from the container and as a further protection and for the purpose of toughening the sealing strip a^6 I usually subject the completed strip to the leatherizing action of formaldehyde or some similarly acting chemical. I sometimes make the paper strip in the form of a long paper tube and then 5 between the several articles arranged thereon I secure the walls of the tube tightly together, as clearly illustrated in Fig. 5, forming in effect a series of sealed pockets or envelopes adapted to contain any material or 10 article which it is desired to dispense from the container, and when the strip is severed at points between the pockets the articles dispensed are still protected from contamination until the individual pockets are 15 20 opened.

In Fig. 6 I have illustrated another form of the strip A. In this instance it consists of a long strip of paper in which a series of swabs F are arranged longitudinally in 25 relation thereto with a portion of the paper between the several swabs F free of any material. In this form the swabs may be withdrawn from the container one at a time and the paper severed between the swabs and 30 thereafter when it is desired to use a swab the paper can be unfolded from the swab, thus insuring delivery in its sterile condition. In a container formed to hold such a 35 series of swabs, the rounded edge b^6 over which the strip is drawn, as the strip is withdrawn from the container, is arranged far enough below the top of the container to permit the swabs to freely rotate within the container to a position where they can be drawn 40 down the exit passage, as clearly illustrated in Fig. 6. The container for articles of this kind, is preferably made relatively deep, so that the free space at the upper part of the container, which it is necessary to provide, 45 does not bear any large relation to the holding capacity of the container. I sometimes arrange the articles on the strip A in groups of articles or materials which may be associated in use or application, such as a swab 50 of cotton followed by a small quantity of powder, or an applicator followed by a swab of cotton for use on the applicator. It will thus be readily understood that my invention is useful for the convenient dispensing 55 in aseptic or hygienic condition of many different materials and devices which could be arranged in suitable groups or sequence.

In Fig. 7 I have illustrated a modified form of container in that that container is 60 provided with a flexible tube H, which serves as the exit passage. This tube is secured to the upper part of the container immediately adjacent to the inlet b^5 and practically forms a closed outlet for the contained material 65 which may be drawn out through this flexible

conduit. This conduit or tube is preferably formed so that its walls contact very closely with the surface of the strip of material which is held within the container as the strip is drawn through the conduit and thus 70 prevents the entrance into the container of pathogenic organisms even though the tube does not always hang down, and also prevents any free interchange of air between the interior and exterior of the container. 75 The container illustrated in Fig. 7 is provided with an outer casing C, similar to that already described by means of which the conduit H is protected at times when the material is not being withdrawn from the 80 container.

In order that the sterile devices which are packed within the containers may be sterilized from time to time in case considerable time elapses between the use of the first article and the use of the last, I prefer to make my containers in such a manner that they may be placed within a sterilizer and properly sterilized without any destructive 85 effects. 90

When I mount the articles upon a continuous strip for removal from the container I sometimes designate the articles in some manner so that the user may readily judge as to the remaining number of articles 95 in the container at any time. I may number the articles in serial order, as shown in Fig. 8, where the articles or the paper strip within which the articles are mounted are shown as being numbered in serial order by the numerals 99, 98, 97, etc. When the strip is arranged within the container we may assume that there will be 100 of the articles in the container and the first one withdrawn would be No. 100 and, as the articles are removed, 100 the numbers designating the articles within the container would always be shown on the projecting end of the strip, as the higher numbers would first be removed.

I wish it particularly understood that 110 while I have made use of the word "sterile" or "aseptic" in describing the condition of the material held within the container, my invention is not limited to the exact meaning of this word, but, on the other hand, the 115 word "sterile" may properly be considered to include hygienic, fresh, or any other word indicating that the material is retained within the container in the condition in which it is placed therein or in the condition in which 120 it is desired to retain the material. Furthermore, while I have shown and described certain specific forms of containers and contained articles and materials, it should be understood that the scope and application 125 of my invention are not thus limited.

Having thus described my invention, I claim as new and desire to secure by Letters Patent:

1. A closed container, a series of aseptic 130

- articles therein, a flexible connector to which the articles are connected in serial order, the container having an elongated closed exit passage open at its ends through which the articles may be removed by means of the connector, the walls of the passage being adapted to close upon the connector between the articles thereon to maintain the container and its contents in aseptic condition
- 5 and to prevent the inadvertent return to the container of the exposed end of the connector.
- 10 2. A closed container for sterile material provided with an elongated tube-like exit passage open at its ends only and through which the material must pass as it is removed from the container, the walls of said passage being adapted to close toward each other upon and yieldable to permit the sterile material to pass.
- 15 3. A closed container adapted to hold sterile material and provided with a downwardly extending exit passage through which the material must pass in a downward direction as it is removed from the container, said passage having walls adapted to close toward each other upon the material therein which normally acts as a stopper for the passage to reduce to a minimum the flow of
- 20 air into and out of the container.
- 30 4. The improvements herein described comprising a container having a chamber to hold sterile material and provided with an elongated closed exit passage communicating at one end with said chamber, the other end serving as an exit opening, said exit opening arranged below the other end of the passage, whereby the sterile material must pass in a downwardly direction as it is removed from the container through said passage.
- 35 5. A closed container in combination with a strip carrying sterile material arranged within the container to be continuously drawn out, said container having an exit
- 40 45 50 passage of appreciable length formed of transversely connected or continuous walls and through which the strip extends, the walls of the passage adapted to frictionally engage the strip and prevent its free return to the container, and a cover incasing the container and adapted to protect the outer end of the strip.
6. A closed container in combination with a paper strip carrying a plurality of sterile articles secured thereon in longitudinally spaced relation, the container being provided with a downwardly extending exit passage closed on four sides through which the paper strip extends and by means of which the articles may be withdrawn one after the other, the strip being adapted to be severed between the articles, and the spacing thereof being sufficient to permit the walls of the passage to close upon the strip, the material in the passage being adapted to act as a stopper therefor.
- 55 7. A closed container for holding sterile material having an exit passage on one side and an exit opening above the bottom thereof, in combination with an open-bottomed cover for normally incasing the container and protecting the exit opening, said container and cover being formed to closely contact with each other below said exit opening to seal the space between the exit opening and the bottom of the container.
- 60 70 75 8. A container for holding sterile material, provided with an outwardly extending wall near its lower end, in combination with an open-ended casing for normally covering the container, said casing being adapted to contact with said outwardly extending wall to seal the space between the container and the casing, and an exit passage opening into the space between the casing and the container and above said inclined wall.
- 80 85 90 95 9. A container for sterile material having an exit opening on one side, a strip adapted to carry sterile material inclosed in the container and adapted to be continuously drawn out through said opening, a casing having an open end adapted to be placed over the container to protect said opening, said casing carrying a knife edge which is adjustable relatively to said opening and whereby the strip may be readily severed.
- In testimony whereof, I have hereunto set my hand this 10th day of August, 1915, in the presence of two subscribing witnesses.
- 100

SIMEON TRENNER.
